UNITED STATES PATENT OFFICE.

LOUIS GODDU, OF WINCHESTER, MASSACHUSETTS, ASSIGNOR TO GORDON MCKAY, OF NEWPORT, RHODE ISLAND, AND JAMES W. BROOKS, OF CAMBRIDGE, MASSACHUSETTS, TRUSTEES.

NAILING-MACHINE.

SPECIFICATION forming part of Letters Patent No. 288,421, dated November 13, 1883.

Application filed September 11, 1883. (No model.)

To all whom it may concern:

Be it known that I, LOUIS GODDU, of Winchester, county of Middlesex, State of Massachusetts, have invented an Improvement in 5 Nailing-Machines, of which the following description, in connection with the accompanying drawings, is a specification, like letters on the drawings representing like parts.

This invention is an improvement on the 10 machine represented in United States Patent No. 265,227, granted to me September 24, 1882, and to which reference may be had.

My present invention comprehends improvements in the chutes which conduct the nails or 15 fastenings to the nose or nail tube, and means to remove the same singly from the chute to be acted upon by the driver or driven into the stock.

In this present invention bevel-wheels located near the end of each roadway of the chute, and having teeth of suitable length, are employed, instead of the sliding bifurcated separators shown in the said patent, and with the 20 said toothed wheels I have combined mechanism whereby either of them may be operated at will to receive and convey to the driver a nail of the proper length, either of the said 25 wheels being actuated at will, according to the length of nail or fastening which it is desired 30 to drive. The spaces or teeth in the said wheels which receive the nails or fastenings are so shaped and proportioned with relation to the nail to be fed by it to the driver that but one nail can enter one space.

35 Figure 1 is a detail showing part of the vibrating head which carries the usual driver and awl-bars and the nail-receiving drum and chute, sufficient in connection with the said patent to illustrate my present improvements.

40 Fig. 2 is a view on a larger scale of the top of the double roadway and rotating separators or wheels, the arms which carry the pawl for actuating the said wheels being in section. Fig. 3 is a section of Fig. 1 in the irregular 45 dotted line $x x$, but on an enlarged scale, to illustrate the cam-shaft and devices for moving the pawl-carrying arm; Fig. 4, a broken elevation from the right of Fig. 1, and Fig. 5

a detail showing the manner of holding the 50 pawls in their arms.

In the drawings, the vibrating head B, driver-bar a , the nail-receiving drum E, the chute m , cover n^5 , the stops $f^3 f^4$, sector f^5 , tube f^8 , spring-pressed pin f^7 , throat c , and shaft C are all as in my patent referred to, and derive motion as therein shown; so need not be herein 55 further described.

The chute m has two roadways, 2 3, and the 60 nails therein will be covered by the cover n^5 . The lower end of the chute is joined with the throat c by a bolt, 5. The throat has vertical 65 passages 7 8 for the usual awl and driver, respectively.

Into the side of each roadway, at or near the 70 lower end of the chute, where the roadways are divided only by the narrow wall 9, I extend the teeth of the rotating separators or 75 bevel-toothed wheels 10 12, mounted, respectively, on pins 13 14, fast in the nose. These separators have the spaces between their teeth 15 16, and the length and width of the teeth so proportioned with relation to the diameter or size of the nails or fastenings 15 16, to be driven, that but one nail at a time can get into one of the spaces of the separators. These separators are moved intermittently one at a time and for any desired number of times in succession by means of pawls, one for each separator.

The separator 12 is moved by a pawl, 17, 80 connected with a lever or arm, 18, having a solid or rigid pin extended through the head B, and having applied to its other end an arm, 20, which is joined by a spring, 21, with a like arm, 22, on the rigid pin 23 of the arm 24, 85 which carries the pawl 25, that turns the separator or wheel 10. Each pawl is connected with its lever or arm by a spring, 26, the flanged and notched end of which enters a groove, 27, at the upper end of the pawl, as 90 shown best in Fig. 5, and, as shown in the said figure, the said pawl is slabbed off, making a corner, 28, against which the said spring bears, so that the point of the said pawl is borne toward and so as to engage the teeth of 95 the said separator and carrier, which receives

from the roadway the nail to be driven and carries it opposite and under the driver-passage 8, in which position the driver in its descent meets the head of the nail and drives it below the carrier into the stock below the usual nose, *c*. In practice the spaces between the teeth of the rotary separators or carriers correspond substantially in shape and size with one-half of the driver-passage.

10 The shaft C, common to the patent referred to, instead of being provided with cams *f*, as in the said patent, is provided with two cams or disks, 30 31, with their acting faces turned toward each other, as shown in Fig. 3, and so that cam 30 will act against the roller stud or pin 32 of arm 18, and the cam 31 against a like roller stud or pin, 33, on the arm 24. Either of the arms 18 or 24 may be so held that the actuating-cam cannot strike and move it, and one or the other of the said arms will be held, according to which roadway is to supply the nails to be driven, for the nails taken from the roadway 3 are removed by the separator and carrier 12, while those from the roadway 2 are removed by the separator and carrier 10. If it is desired to lock out of action the arm 18, pawl 17, and the separator 12, and enable the arm 24 to move the separator and carrier 10, to take nails from the roadway 2, then the usual tube, *f*⁸, will be turned in the proper direction to cause the stop *f*³ to act upon the arm 18 and hold it back, so that the cam 30 cannot strike it. Such movement of the tube *f*⁸, to enable the stop *f*³ to hold the arm 18, draws back the stop *f*⁴ and permits the spring 21 to hold the roller-stud 33 of arm 24 against the cam 31, so that the said cam effects the movement of the pawl 25 backward over the teeth of the carrier 10, and when the 40 said pawl engages a new tooth the cam 31, by its change of position and owing to its shape, has reached such a point as to permit the spring 21 to become the mover for the arm 24 and pawl 25, the latter then turning the separator and carrier 10 far enough to take a nail, 16, from the roadway 2 and carry it into position under the driver.

In practice the separator or carrier will be acted upon by a suitable friction device to prevent them moving farther than they are positively to be moved by the pawls. The operator desiring a different length of nail from that which the machine is then driving will turn the tube *f*⁸ and set it so that the change 55 to bring the other length of nail into operation will be effected automatically as soon as the cams 30 31 arrive in the proper position to enable the stops to move and effect the change

desired automatically—as, for instance, if the tube *f*⁸ is shifted to force in the stop *f*³ at the 60 left of Fig. 1 at a time when the arm 18 is directly in front of it, the said stop cannot get behind the said arm to hold it until the cam 30 moves the said arm past its end. While the stop is waiting its chance to operate, as it 65 may be said, the spring which acts on the usual spring-pin, *f*¹, is compressed.

Referring to Fig. 2, it will be seen that the narrow division-wall 9 of the chute between the two roadways comes to a taper, and the 70 end of the said wall is made to form part of the driver-passage, and the heads of the nails 15 and 16, the bodies of which are engaged by the separators and carriers, rest upon and are supported by the said wall up to the driver-passage, and the opposite side of the head is supported upon the moving separator, so the 75 separator acts to carry the head along on the said wall up to the driver-passage.

I claim—

1. The chute and two roadways, combined with two rotating separators provided with teeth which project into the said roadways, and which are adapted to carry nails from either of the said roadways at will to the driver-passage, substantially as described. 80 85

2. The chute and a roadway therein for nails, and a rotating separator having its teeth extended into the said roadway to separate and remove the nails, combined with a pawl 90 and arms to carry it, and means to operate the said arm intermittently, whereby the said separator is also operated intermittently, substantially as described.

3. The chute and two roadways, and two rotating separators made as toothed wheels, and having their teeth extended into the said roadways, combined with two arms and pawls, either of which may be operated at will, and the other held out of operation to enable either one of 100 the two separators to present in the driver-passage nails from the roadway with which it co-operates, substantially as described. 95

4. The chute provided with two roadways and a division-wall tapered at its end next to 105 and terminating at the driver-passage, combined with the two rotating separators, to operate substantially as described.

In testimony whereof I have signed my name to this specification in the presence of two subscribing witnesses.

LOUIS GODDU.
